Shelton J. Gunn Inventor
By *Paul E. Hayes* his Attorney

UNITED STATES PATENT OFFICE.

SHELTON J. GUNN, OF GUNNTOWN, FLORIDA.

IRON-BOUND COVER AND BOX CONSTRUCTION.

Application filed August 3, 1922. Serial No. 579,405.

To all whom it may concern:

Be it known that I, SHELTON J. GUNN, a citizen of the United States, residing at Gunntown, in the county of Levy and State of Florida, have invented certain new and useful Improvements in Iron-Bound Cover and Box Construction, of which the following is a specification.

My invention relates to an improvement

- 10 in iron bound cover and box construction, and is an improvement on the invention disclosed in my application Serial No. 507516, filed in the U. S. Patent Office on October 13, 1921, the present invention differing 15 from the above-mentioned invention in the means for securing the metal binding to the box cover or part.

This invention therefore consists in a metal binding made by folding sheet-metal

- 20 around the edge of the box part, and securing it thereto by crimping the edge, and forcing said crimped edge as formed into the material of the box or cover, whereby it is inseparably connected therewith and 25 made part and parcel thereof.

In the accompanying drawings:

Fig. 1 is a plan view;

Fig. 2 is an enlarged longitudinal section;

Fig. 3 is an enlarged fragmentary trans-

- 30 verse section.

A, represents a box cover or bottom; and 1, is the iron binding at the ends made by folding a strip of thin sheet-metal around the edge, preferably by a machine devised 35 for the purpose. The edges of the metal on both sides of the box part are corrugated and crimped, as at 2, and forced into the grain of the wood lengthwise of the same, preferably by machinery devised for the 40 purpose, whereby the binding is made fast and inseparable from the box cover, bottom or other part. The ends 3 of the metal

bands or binding are brought together and protrude beyond the edge of the part to which the binding is secured as a means for 45 fastening the iron bound part, if a cover or bottom, to the body of the box.

It is preferably obvious of course that the material to which this is applied may be veneer, sawed lumber, fibre-board, or the 50 like.

A cover or bottom or part thus made is cheaply constructed, and the crimping is a most effective means of forming an inseparable union between the binding and the 55 part bound, the crimping being a means of connection which lends itself readily to a machine devised for the purpose of applying and fastening these bands or binding to the edge of the box stock. 60

I claim:

1. The combination with a member adapted to serve as a box cover or bottom, of a substantially U-shaped metal binding-strip enfolding an edge of the member, and at 65 least one edge of the binding crimped transversely and forced into the body of the material bound, whereby to secure the binding to the stock.

2. The combination with a member adapted to serve as a box cover or bottom, of a substantially U-shaped metal binding-strip enfolding an edge of the member, and at 75 least one edge of the binding crimped transversely and forced into the body of the material bound, whereby to secure the binding to the stock, and the ends of the binding protruding beyond the edges of the stock to afford a means for fastening the bound article in place. 80

In testimony whereof I affix my signature.

SHELTON J. GUNN.
